UNITED STATES PATENT OFFICE

2,524,592

DRUMHEAD CONSTRUCTION

Charles P. Cordes, Hillside, N. J.

Original application May 3, 1944, Serial No. 533,878. Divided and this application April 18, 1947, Serial No. 742,284

2 Claims. (Cl. 84—411)

1

This invention relates to the head construction of percussion drums, and the present application is a division of my pending application Serial No. 533,878, filed May 3, 1944, now Patent No. 2,433,200.

The primary object of the present invention is to provide an improved flesh hoop for drums of the above kind.

Another object is to provide an improved flesh hoop, and a thrust ring coating in a novel manner with said flesh hoop to effectively retain the edge of the skin about the latter.

The exact nature of the present invention will become apparent from the following description when considered in connection with the accompanying drawings, in which:

Figure 1 is a fragmentary central longitudinal sectional view, partly broken away, of one end portion of a percussion drum having a head construction embodying the present invention;

Figure 2 is a plan view of the flesh hoop forming part of the head construction shown in Figure 1;

Figure 3 is an enlarged section taken on line 3—3 of Figure 2.

Referring in detail to the drawings, 5 indicates the shell of a snare drum. One end of the shell 5 is inwardly offset at 6, or externally reduced in diameter, to provide the reduced end portion 7 and an external annular shoulder 8 at the inner end of the reduced end portion 7. Snuggly fitted on the reduced end portion 7 is a ring 9 that has an external thread at 9a. The ring 9 is seated flatly on the shoulder 8 and may be secured to the shell 5 by means of screws 10 passing through the ring 9 and threaded into the shell 5. A retaining hoop 11 having an internal screw thread 11a is screwed at its inner portion upon the threaded ring 9 so as to be adjustable longitudinally of the shell 5, and this retaining hoop has an annular inwardly projecting flange 12 at its outer end. The inner portion of flange 12 is preferably inclined inwardly as shown clearly in Figure 1.

A tensioning ring 13 is threaded in the outer portion of the retaining hoop 11 and has its outer periphery provided with external gear teeth 14 so that it also constitutes a ring gear. The inner portion of the outer face of tensioning ring 13 is also preferably inclined inwardly as at 13a, the same as the flange 12 of hoop 11. At a suitable point circumferentially thereof, the retaining hoop 11 is provided with a transverse hollow rib 15 having a cylindrical bore 16 parallel with the axis of shell 5 and in which

2

is journaled a pinion 18. As disclosed in my above-mentioned patent, the pinion 18 meshes with the teeth 14 of tensioning ring 13, and the thread grooves 17 of ring 13 intersect the teeth 14 of the latter. The end portion 7 of shell 5 is in spaced relation to the retaining hoop 11 so as to provide an annular space therebetween. Disposed in this annular space inwardly of the tensioning ring 13 is a flesh hoop 20 consisting of an annular channel of substantially V-shape in cross section and having inturned flanges 21 along the free edges thereof. The usual skin disc or sheet 21 is stretched over the end of the reduced portion 7 of shell 5 and has its marginal portion wrapped about the flesh hoop 20 with its free marginal portion 20' tucked into the channel of hoop 20 through the open outer side of the latter. It will be noted that an annular space 22 is provided between the flanges 21, and that the skin is extended across this space, then downwardly, inwardly and outwardly about the hoop 20, the margin 20' of the skin being finally extended over the inner one of the flanges 21' and beneath the adjacent portion of the skin before being tucked into the channel of hoop 20 as described.

Disposed between the tensioning ring 13 and the hoop 20 is a thin thrust ring 22 having a central inward annular corrugation 23 which is slightly narrower than and arranged to register with the opening or space 22' in the outer side of the flesh hoop 20. Bearing balls 24 are carried by the inner surface of tensioning ring 13 and arranged to engage in the groove formed by the corrugation 23 of thrust ring 22. This construction permits free rotation of tensioning ring 13 relative to thrust ring 22 and allows the latter to remain still or to be held stationary by its frictional contact with the adjacent portion of the skin 21 when the said ring 13 is rotated to thread the same inwardly and thereby cause corresponding movement of thrust ring 22 and flesh hoop 20 to place the skin 21 under tension. Obviously, such inward movement of flesh hoop 20 will cause the margin of skin 21 to be stretched over the outer end edge of the end portion 7 of shell 5 until the skin has been properly tensioned. By rotating pinion 18, the tensioning ring 13 may be turned to thread the same inwardly. When this is done, the corrugation 23 of ring 22 forces the adjacent portion of skin 21 into the space 22' of hoop 20, thereby effectively binding and securing the marginal portion of the skin to the flesh hoop. In actual practice, the margin of the skin is preferably wetted, and when it dries the

free edge portion 25 thereof will curl up within flesh hoop so that the skin may not readily become detached from the latter. The pinion 18 may have an axial polygonal bore 25 for reception of the square shank of a suitable handle employed for rotating the pinion 18.

As the thrust ring 22 may remain stationary when the tensioning ring 13 is rotated, there is no tendency to cause the skin 21 to rotate with the tensioning ring 13, even though the ring 22 bears upon the skin 21. Thus, the skin will be drawn evenly at all points so as to be tensioned in a very smooth condition.

From the above description, it will be seen that I have provided a simple and efficient flesh hoop, and that the flesh hoop and thrust ring are so constructed as to coact in a novel manner for effectively retaining the margin of the skin about the flesh hoop.

Having described my invention, what I claim as new is:

1. In a percussion drum, in combination, a shell, a flesh hoop loosely disposed about the top end of said shell and comprising an annular channel member having spaced edge flanges at the top projecting toward each other, a skin disk stretched over said end of the shell and having its marginal portion extended across the top and then about the sides of said flesh hoop with its free edge portion extended under the adjacent portion of the skin disk and tucked into the flesh

hoop between said flanges of the latter, a thrust ring disposed above said flesh hoop and having a central downward annular corrugation engaging the portion of said skin between said flanges of the flesh hoop, and manually operable means carried by said shell for forcing the thrust ring downwardly to correspondingly move the flesh hoop relative to the shell and thereby tension said skin disk.

5 2. The construction defined in claim 1, wherein said means includes a rotatable tensioning ring disposed above the thrust ring and having bottom bearing balls engaged in said corrugation of the thrust ring.

10 15 CHARLES P. CORDES.
